MACHINE FOR GRINDING SPRINGS.

1,227,498.

Specification of Letters Patent. Patented May 22, 1917.

Application filed May 1, 1916. Serial No. 94,598.

To all whom it may concern:

Be it known that I, FRANK H. SLEEPER, a citizen of the Dominion of Canada, residing at Worcester, in the county of Worcester and Commonwealth of Massachusetts, United States of America, have invented a new and useful Improvement in Machines for Grinding Springs, of which the following, together with the accompanying drawings, is a specification.

The present invention relates to a machine for grinding the ends of coiled springs, and the same contemplates the successive presentation of the ends of a large number of springs to a suitable grinding element by the automatic devices hereinafter described.

An object of the invention is to provide mechanism for this purpose which is substantially universal, in the sense that it is capable of operating upon springs which differ in size over a wide range, as regards both length and diameter.

A further object is to provide a machine of this class which affords easy adjustment of the pressure with which the springs are held against the grinding element, particularly with reference to the beginning of the grinding operation, when it is highly desirable that only a light grinding cut be taken.

30 A further object is to provide an arrangement of parts which insures substantially even and uniform wear on the surface of the grinding element, notwithstanding the fact that each spring, at any given instant, is in contact with only a small portion of the total surface of said element.

40 A further object is to provide for the automatic ejection of the springs from the machine, as each successive spring passes beyond the influence of the grinding element and, if desired, to impart to each spring at this point an independent rotative movement, whereby the wear upon the grinding element is reduced and the end of the spring is more uniformly ground.

45 Other and further objects of my invention are set forth fully in the following description of the mechanism, reference being had to the accompanying drawings, in which—

50 Figure 1 is a top plan view of a machine embodying my invention.

Fig. 2 is a side elevation of the machine, parts thereof being broken away and shown in longitudinal vertical section.

Fig. 3 is a vertical cross section of the machine on the line 3—3 of Fig. 2, a portion of the spring carrying turret being removed for the sake of clearness.

Fig. 4 is a view of the mechanism at the right hand end of Fig. 2, parts being broken away to disclose the mechanism for rotating the spring carrying turret.

Fig. 5 is a diagrammatic representation of the path of a spring, in relation to the surface of the grinding element, disclosing the arrangement of parts relied upon to prevent uneven wear of said surface.

Fig. 6 and 7 are fragmentary views, in side elevation and in section respectively, of the rim of the spring carrying turret, disclosing the adjustable attachment of the spring holding arbors thereto.

Like reference characters refer to like parts in the different figures.

Referring to the drawings, the mechanism is preferably arranged upon a base casting 1, which supports bearings 2, 2 for a horizontal shaft 3. The shaft 3 is driven in any suitable manner, as by means of a belt pulley 4, operated from any suitable source of power, not shown. Secured to the end of the shaft 3 is a wheel 5, which supports, on its outer face, a concentric annular grinding element 6, made of any suitable abrasive material. The grinding element 6 is preferably detachably secured to the wheel 5, in order to permit its removal, when desired, for repair or replacement; as shown in Fig. 2, an annular removable wedge shaped member 7 may be employed for this purpose, or any other well known expedient may be adopted to retain the grinding element in position upon the wheel.

For the presentation of the ends of the springs to be ground to the face of the rapidly rotating grinding element 6, a revolving turret 8 is employed, the same providing a plurality of spring supporting arbors 9 facing the grinding surface of the element 6. The arbors 9 are seated in V-shaped notches 10 on the periphery of the turret 8, as shown in Figs. 6 and 7, and each pair of adjacent arbors is firmly retained in position by means of a clamp 11 which spans the space between the two arbors and is held in firm engagement with each by means of a screw or bolt 12 entered into the rim of the turret. The loosening of a bolt 12 permits adjust-

ment of the two arbors held thereby toward or from the face of the grinding element 6, and when the desired adjustment has been made, the tightening of the bolt 12 holds the 5 arbors 9 firmly in adjusted position.

The turret 8 is keyed to a shaft 13, and is capable of longitudinal adjustment thereon by means of a set screw 14. The shaft 13 is journaled at its opposite end in a bearing 15, the longitudinal axis of which is offset laterally with respect to the axis of the shaft 3, as shown clearly in Fig. 3. The bearing 15 is supported for swinging movement about the transverse axis afforded by 10 the trunnions 16, the latter being provided by brackets 17 extending upwardly from a plate 18 which rests on the flat surface of the base 1. The bearing 15 is preferably integral with a housing 19, within which a 15 worm gear 20, fast on the outer end of shaft 13, is disposed. The worm gear 20 is in mesh with a worm 21, also disposed within said housing and driven from any suitable source of power, not shown, by means of a 20 belt pulley 22. An arm 23, preferably integral with the bearing 15 and housing 19, projects downwardly therefrom between the brackets 17, 17, and provides in effect a lever by means of which the bearing, the 25 housing and the other associated parts may be swung about the transverse axis afforded by the trunnions 16. To this end the arm 23 has a projection 24 which is disposed between the ends of oppositely engaging screw 30 bolts 25, 25, the latter being mounted in upstanding lugs 26, 26 at the ends of plate 18. The adjustment of the screw bolts 25, as will be apparent, determines the position of the arm 23, and thereby fixes the inclination 35 of the shaft 13, with respect to a horizontal plane. The plate 18 which supports the entire bearing, driving and adjusting devices of the shaft 13, as above described, is itself adjustable longitudinally of the base 40 1 by means of a screw 27 operated by a hand wheel 28. The longitudinal movement of said screw is communicated to the plate 18 by means of a yoke 29, and the plate is guided in its movement by means 45 of longitudinal slots 30 therein which cooperate with bolts 31 projecting upwardly from the base 1.

By reason of the offset or eccentric disposition of the shaft 13, the paths described 55 by the springs, carried around by the rotating turret 8, intersect the face of the grinding element 6 in the manner diagrammatically indicated in Fig. 5, where the shaded wide annular portion indicates the 60 face of the rapidly rotating grinding element, and the unshaded narrow annular portion indicates approximately the path of each spring. As shown in said figure, this arrangement of parts provides at all times 65 for the exposure of a number of the annu-

lar series of arbors 9, at one side of and beyond the grinding wheel 5, whereby the springs may be readily placed on said arbors and removed therefrom without interference by the grinding wheel. Moreover, 70 as indicated in Fig. 5, each spring during its engagement with the grinding element 6 traverses the annular face thereof from the outer periphery to the inner periphery, and then across again to the outer periphery. 75 The grinding face of the element 6 is thus subjected to even and uniform wear, which obviously would not be the case if the springs were carried in a path concentric thereto.

The springs to be ground are strung, by hand, upon the arbors 9 as the latter, in the relatively slow rotation of the turret 8, successively reach that portion of their path which lies to one side of the grinding surface, as shown clearly in Figs. 1, 3 and 5. The arbors 9 are previously adjusted, by the devices 11 and 12 above described, to project the requisite distance from the face of the turret 8, in order to provide support 80 for each spring throughout nearly its entire length, sufficient clearance always being maintained between the ends of said arbors and the face of the rotating grinding element 6. It will be clearly understood 85 that the arbor retaining devices, as herein described, enable the use of sets of arbors which differ in diameters over a wide range, thus adapting the machine for the grinding of practically any and all sizes of springs. 90

In the rotation of the turret 8 in the direction of arrow *a*, Fig. 5, the springs thus held on the arbors are successively carried into contact with the face of the element 6, first engaging the same at or near the point 105 32, Fig. 5. The adjustment of the screw bolts 25, 25 to impart an upward inclination to the shaft 13, in the direction of the grinding wheel, throws the turret 8 slightly out of a vertical plane, so that the springs supported at any given instant by the top of said turret project outwardly a less distance than the springs near the bottom thereof. 110 As a consequence, the grinding begins at the point 32 with a very light cut, which gradually increases in depth as each spring progresses downwardly across the face of the grinding element, in the path indicated in Fig. 5. Obviously, the result thus obtained is a highly desirable one; and it will be 115 noted further that for the best results, the parts may be so proportioned and arranged that the springs may be caused to engage and to leave the grinding surface at points corresponding respectively to the minimum 120 and maximum depth of cuts, and at the same time obtain the maximum length of travel across the face of said surface. However, my invention is not in any way limited to the arrangement and proportion of 125 130

parts herein shown, it being obvious that the relative diameters of the grinding surface and the path of the springs, the amount of offset or eccentricity of the shafts 3 and 13, and the inner diameter of the annular grinding surface, are all factors which are capable of variation over a wide range, without departing from the spirit of my invention.

10 As the springs are about to leave the surface of the element 6, at or near the point 33, Figs. 3 and 5, it is desirable that they be rotated on the axes of their respective arbors, in order to decrease the wear upon the outer edge of said surface, and to prevent possible chipping thereof by the springs, and also to insure a more uniform grinding of the ends of the springs. To accomplish this result, a belt 34, or other device presenting a flexible friction surface, 20 may be loosely suspended so as to make contact with the springs as they approach the point 33; said belt being herein shown as passing over a roller 35 which is disposed somewhat above the point 33, so as to insure contact between belt and springs for an appreciable distance. The belt 34 is held yieldingly against the springs by a weight 36, and the rolling contact thus effected causes the 25 springs to rotate on the axes of their respective arbors. The other end of the belt 34 may be attached to any desired part of the machine; for convenience it is here shown as attached to an arm 37.

30 The discharge of the springs from the arbors 9, after each has left the face of the grinding wheel is accomplished automatically by means of a rotating toothed or corrugated member 38, disposed in the path of the springs, and attached to a shaft 39 which is journaled in the arm 37. The shaft 39 is rotated by means of a belt 40, which encircles a pulley 41 thereon and which is guided around a pulley 42 on the shaft of worm 21 by means of a guide pulley 42'. The arm 37 is pivoted at 43 to the base 1, and its free end, carrying the rotating ejector 38, is drawn yieldingly toward the periphery of the turret 8 by a spring 44, a stop 45 being provided to limit the inward movement of said arm. Each spring carried upwardly from the point 33 is wiped past the rotating member 38, whose corrugations or teeth successively engage the 45 convolutions of the spring, to move the latter longitudinally of its arbor, and off the end of the same whence it may fall by gravity into a suitable receptacle provided for this purpose. The ejector 38 is preferably 50 frusto-conical in form so that its effective surface conforms substantially to the path followed by each spring, during the time in which it is acted upon by said ejector. By reason of the yielding connection between 55 the arm 37 and the base 1, the member 38

automatically adjusts itself to the diameter of any spring that is presented thereto, as above described.

I claim,

1. In a spring grinding machine, a grinding element, and means for successively presenting the ends of the springs to said element, comprising a series of fixed arbors on which said springs are strung. 70

2. In a spring grinding machine, a series 75 of arbors for supporting the springs to be ground, means for fixing said arbors to correspond to the lengths of the springs, and means for adjusting said arbors to correspond to the lengths of the springs. 80

3. In a spring grinding machine, a work carrying element providing a series of arbors for supporting the springs to be ground, and means for detachably securing said arbors to said work carrying means, said means 85 being adjustable for arbors of different diameters.

4. In a grinding machine, a work carrying element providing a plurality of peripheral notches, a work supporting arbor 90 adapted to seat in each notch, and adjustable means for clamping said arbors in operative position.

5. In a grinding machine, a work carrying element providing a plurality of peripheral notches, a work supporting arbor adapted to seat in each notch, and a plurality of 95 adjustable clamps, each operative with respect to two of said arbors, for securing the same to said work carrying element. 100

6. In a spring grinding machine, a grinding element, means for successively presenting the ends of the springs to said element, comprising a series of arbors on which said springs are strung, and means for rotating 105 each spring on its arbor.

7. In a spring grinding machine, a revolvable grinding element, means for moving the springs to be ground thereby in a path eccentric to the axis of said element, and means 110 for rotating each spring as it reaches a predetermined point in said path.

8. In a spring grinding machine, a revolvable grinding element, means for moving the springs to be ground thereby in a circular 115 path, a portion of which lies to one side of said grinding element, and means for rotating each spring as it approaches said portion of its path.

9. In a spring grinding machine, means 120 for moving the springs to be ground in a circular path, and means for rotating each spring about its own axis during a portion of its movement in said path.

10. In a grinding machine, an annular rotating grinding element, and means for moving each article to be ground in a circular path intersecting the outer and inner peripheries of said annular grinding element. 125

11. In a grinding machine, a circular ro- 130

- tating grinding element, means for moving each article to be ground in a path intersecting the periphery of said element at a plurality of points, and means for rotating each article as it approaches one of said points. 5
12. In a grinding machine, an annular rotating grinding element, means for moving each article to be ground in a circular path intersecting the outer and inner peripheries 10 of said annular grinding element, and means for rotating each article as it approaches the outer periphery of said element.
13. In a spring grinding machine, a revoluble grinding element, means for moving 15 the springs to be ground in a circular path, into and out of contact with the surface of said grinding element, and means for fixing said path in a plane inclined to said surface.
14. In a spring grinding machine, a revoluble grinding element, means for moving 20 the springs to be ground in a circular path, into and out of contact with the surface of said grinding element, and means for varying the inclination of the plane of said path 25 with respect to said surface.
15. In a grinding machine, a revoluble grinding element, a work supporting turret facing said grinding element and rotatable on an axis offset from the axis of said grinding 30 element to carry the work into and out of contact with the surface of said grinding element, and means for tilting said turret at an angle to said surface.
16. In a grinding machine, a revoluble 35 grinding element, a work supporting turret facing said grinding element and rotatable on an axis offset from the axis of said grinding element to carry the work into and out of contact with the surface of said grinding 40 element, and means for varying the angular relation between the face of said turret and the surface of said grinding element.
17. In a spring grinding machine, a grinding element, means for successively presenting the ends of the springs to said element, 45 comprising a series of arbors on which said springs are strung, and automatic means for removing the springs from said arbors after the grinding operation.
18. In a spring grinding machine, a grinding element, means for successively presenting the ends of the springs to said element, 50 comprising a series of arbors on which said springs are strung, automatic means for removing the springs from said arbors after 55 the grinding operation, consisting of a rotating member adapted to engage each spring after grinding thereof and move it lengthwise off its arbor.
19. In a spring grinding machine, a grinding element, a spring carrying turret for moving the springs to be ground in a predetermined path, and a member operative to discharge the springs from said turret as each reaches a predetermined point in said 60 path. 65
20. In a spring grinding machine, a grinding element, a spring carrying turret for moving the springs to be ground in a predetermined path, a member operative to discharge the springs from said turret as each reaches a predetermined point in said path, and means for yieldingly retaining said member in said path. 70
21. In a spring grinding machine, a grinding element, a spring carrying turret for moving the springs to be ground in a predetermined path, a member operative to discharge the springs from said turret as each reaches a predetermined point in said path, 75 and means for yieldingly retaining said member in said path, said member being supported to adjust itself to the size of the springs. 80
